FIG. 1

FIG. 2

INVENTOR.

CHARLES J. HODGES.

BY

Lockwood & Lusk

ATTORNEY.S.

UNITED STATES PATENT OFFICE.

CHARLES J. HODGES, OF ANDERSON, INDIANA, ASSIGNOR TO THE QUALITY TIRE & RUBBER COMPANY, OF ANDERSON, INDIANA, A CORPORATION.

DESIGN FOR AN AUTOMOBILE-TIRE.

54,740.

Specification for Design.

Patented Mar. 23, 1920.

Application filed November 24, 1919. Serial No. 340,420. Term of patent 14 years.

To all whom it may concern:

Be it known that I, CHARLES J. HODGES, a citizen of the United States of America, residing in the city of Anderson, county of Madison, and State of Indiana, have invented a new and original and ornamental Design for an Automobile-Tire, of which the following is a specification, reference being had to the accompanying drawings, forming a part thereof.

In the drawings, Figure 1 is a plan view of the automobile tire, showing my new design, and Fig. 2 is a sectional view thereof.

I claim:

The ornamental design for an automobile tire, as shown.

CHARLES J. HODGES.
